UNITED STATES PATENT OFFICE.

ARTHUR E. DOWELL, OF WASHINGTON, DISTRICT OF COLUMBIA, ASSIGNOR,
BY MESNE ASSIGNMENTS, TO DETROIT TRUST COMPANY, TRUSTEE, OF
DETROIT, MICHIGAN, A CORPORATION OF MICHIGAN.

PRINTING-PRESS.

SPECIFICATION forming part of Letters Patent No. 702,546, dated June 17, 1902.

Application filed September 20, 1901. Serial No. 75,841. (No model.)

To all whom it may concern:

Be it known that I, ARTHUR E. DOWELL, of Washington, in the District of Columbia, have invented certain new and useful Improvements in Printing-Presses; and I hereby declare that the following is a full, clear, and exact description thereof, reference being had to the accompanying drawings, which form part of this specification.

This invention is an improvement in means for actuating looping-rollers of web-handling machinery and the looping-rollers of type web-perfected printing-presses in which an intermediate part of a continuously-moving web is intermittently retarded or stopped and started by means of looping bars or rollers, and the invention is particularly designed for use in flat stationary bed reciprocating impression-cylinder web-presses of the type known as "Cox duplex" perfecting-presses, and in the accompanying drawings the invention is illustrated as applied to such a press; but of course the invention may be used wherever movable looping-rollers are employed to control the movement of the web and wherever it is desired to provide means for varying the throw or extent of lateral reciprocating movement of a looping-roller, so as to cause it to take up and give off more or less web in a given interval of time.

The object of the invention, therefore, as applied to the Cox duplex press is to enable the throw of the looping-rollers to be varied while using the same cam mechanism or to vary the amount of movement of the web-looping rollers in accordance with the speed of the continuous in-feed and out-feed of the web, so that the press can be readily adapted to operate upon different lengths of sheets without changing the cam mechanism which operates the looping-rollers.

In the Cox duplex press as heretofore made but one length of sheet could be printed upon, the length of such sheet being controlled by the speed of the feed-rollers and the cam mechanism operating the looping-rollers being designed and adapted to take care of but one length of sheet. By my invention the speed of the web-feed rollers in such presses may be varied by any usual means, so as to feed in more or less web during each reciprocation of the cylinders. This means for vary-

ing the feed of the web, not forming part of the present invention and being old, is not illustrated herein; but of course if the feed varies the movement of the looping-rollers must be proportionately varied, else the tension of the web would be lost or the web would be ruptured, and in either case the machine would be practically inoperative.

The following description explains my invention as applied to the Cox duplex press, which is fairly shown in Patents No. 478,503 of July 5, 1892, and No. 501,456 of July 11, 1893; but the adaptability thereof to other uses in other machines will be obvious.

In the accompanying drawings, Figure 1 is a detail sectional view of the web-looping mechanism of a Cox duplex press with my improvements applied thereto. Fig. 2 illustrates a modification of the invention, and Fig. 3 illustrates another modification.

Referring to the drawings, K K designate a set of feed-rolls and tapes, by which the web is drawn into the press from the web-roll W. The web w passes up over a looping-roller l, thence down under a guide-roller M to and through the printing mechanisms of the press, (not shown,) back over an upper looping-roller M', down under an internal looping-roller l', and thence up to the delivery-rolls O O, as indicated in Fig. 1. The feed and delivery rollers K and O are driven at a uniform speed by means of a connecting train of gearing, so that the web is continuously fed into and out of the press at a uniform rate.

The looping-rollers l l' are journaled in a reciprocating frame L, which is moved up and down by a cam mechanism at such rate and in such time that during the taking of an impression the lower looping-roller l takes up all the web that is fed in by rolls K, and during the same time the upper looping-roller l' gives out the web as it is required by the continuously-running delivery-rolls O. Therefore during the taking of an impression that portion of the web between the guides M and M' is stopped.

After the impression is made the frame L is lowered, so that the loop of web formed on the lower roll l is given off, while a like quantity of web is taken up in the elongated loop formed by the descent of the looping-roller l'.

Heretofore this looping-frame *l* has been reciprocated by means of a race-cam *D* and a vibrating lever *A*, having a cam-roller *d* running in the groove of cam *D*, the free end of lever *A* being connected to the lower extremity of the frame *L*, as in Cox's patent, No. 501,456. By this construction the looping-rollers *l* had given only one predetermined extent of vibration and their throw could not be altered to accommodate variable feed and delivery of the web except by changing the cam *D*, which was virtually impractical. The parts thus far described are old.

My present invention consists in providing the vibrating lever by which the looping-frame *L* is operated with an adjustable fulcrum, by shifting which the throw imparted to the frame from the same cam *D* may be varied—*i. e.*, made greater or less—so that the looping-rollers may be easily adjusted to take care of variable lengths of web fed in and delivered from the press by the feed and delivery rollers *K* and *O*, which are preferably driven by gearing so proportioned that the desired length of web will be fed and delivered by the rolls *K* and *O* for each rotation of the cam *D*. As shown, rolls *K* are driven from the cam-shaft by means of a gear *E*, an intermediate *E'*, and a pinion *E²* on the shaft of one roll *K*. By substituting different-sized pinions *E²* on the roll-shaft and shifting gear *E'* so as to continue to mesh therewith and with gear *E* the speeds of the feed-rolls can be easily varied.

As shown in Fig. 1, a lever *B* is pivoted just above lever *A*, and its front end is connected to the lower end of frame *L* by a link *b*. The pivot of lever *B* is considerably nearer the frame *L* than the pivot of lever *A*. Upon lever *A* is an adjustable fulcrum *a*, upon which the lever *B* is supported. Lever *A* may be held down by a spring *A'*, if desired, and lever *B* may be held down by a spring *B'*, as indicated in Figs. 1 and 2. It will be seen that lever *B* is vibrated by and from lever *A*, to which a uniform throw is imparted by the cam *D*; but the throw of lever *B* is variable and depends upon the position of the fulcrum *a* on lever *A*. If this fulcrum is adjusted to the extreme outer end of lever *A*, as indicated in Fig. 1, lever *B* will be moved to the least extent; but if the fulcrum *a* is moved inward toward the cam *D* the extent of throw of lever *B* will be increased more and more as the fulcrum approaches the cam. This variation in the throw of lever *B* is due to the fact that its pivot is so far in advance of the pivot of lever *A* that although the vertical movement of the fulcrum *a* decreases as it is moved toward the pivot of lever *A* the throw of lever *B* is increased in a greater proportion, because the fulcrum *a* operates on lever *B* so much nearer the pivot thereof. This is obvious from the drawings and further explanation appears unnecessary. By properly adjusting the fulcrum on lever *A*, therefore, the looping-frame *L* can be given any desired

throw between certain extremes, and thus can be adjusted to take care of any length of web that may be handled by the feed and delivery rollers during the impression. The proper position of the fulcrum to compensate for varying feeds of the web can be calculated beforehand and marked upon the levers *A* or *B*, so that the pressman after putting the proper driving-pinion *E²* on the feed-roll shaft can adjust the fulcrum *a* to the corresponding proper point on the lever. As shown, the fulcrum may be shifted by a screw-shaft *a²*, but the particular form of the fulcrum *a* and the means for shifting it are not essentials of the invention.

In the modification shown in Fig. 3 the upper lever *B* is pivoted at its front end at a point beyond the frame *L*. Consequently when the fulcrum *a* is at the extremity of lever *A* it will impart the greatest movement to the lever *B²*, and when the fulcrum *a* is shifted toward the cam-roller *d* the throw of lever *B²* will be lessened. The operation and effect of the device, however, are substantially the same as in the construction shown in Fig. 1.

In Fig. 3 the secondary lever *B* and *B²* is omitted, but the lever *A* is extensible, being provided with a telescopic portion *A²*, which is pivoted to the fulcrum *A³*, which is adjustable on the frame. As shown, it is adjustably secured to a rib *A⁴* on the main frame. By adjusting the fulcrum *A³* toward or from the cam-roller *d* the extent of vibration of the lever will be varied, and consequently the rise and fall of the looping-frame *L* will be correspondingly varied. This latter modification I do not consider as desirable as either of the former, because a much greater linear adjustment of the fulcrum will be necessary than in the other modifications to correspondingly vary the throw of the looping-frame *L*.

I do not wish to confine myself to the particular construction or application of the device herein described except where specifically mentioned in the claims, as the principle of the invention once disclosed may be embodied in various constructions and utilized in various machines.

Having thus described my invention, what I therefore claim as new, and desire to secure by Letters Patent thereon, is—

1. In a printing-press, the combination of web-forwarding mechanism a web-looping roller, a vibrating lever for operating said looping-roller, a cam for operating said lever, and a fulcrum for said lever adjustable to and from the cam whereby the extent of vibration of both lever and looper may be regulated, substantially as described.

2. The combination of changeable-speed web-forwarding mechanism a web-looping roller, a vibrating lever operating the looping-roller, a cam for vibrating said lever, and an adjustable fulcrum below and directly engaging the under side of the lever and adjustable to and from the cam whereby the throw

thereof produced by the cam and the throw of the looping-roller may be varied, substantially as described.

3. The combination in a printing-press, of 5 web-feed rollers, a looping-roller adapted to take up the web fed in by the feed-rollers during an impression, a pivoted lever for operating the looping-rollers, a second pivoted lever for operating the first pivoted lever, an 10 adjustable fulcrum between the first and second levers, and means for vibrating the second lever, substantially as described.

4. The combination in a printing-press of 15 web-feeding devices and means for changing their speed, a looping-roller adapted to take up the web fed in thereby during an impression, a pivoted lever for operating the looping-roller, a second pivoted lever and an adjustable fulcrum thereon for operating the 20 first pivoted lever, and means for vibrating the second lever, substantially as described.

5. The combination of continuously-operating changeable-speed web-feeding rolls, a 25 movable looping-roller for giving an intermittent movement to the web, a vibrating lever for operating the looping-roller, a cam for actuating said lever, and an adjustable fulcrum for said lever adjustable to and from the cam whereby the throw of the lever and 30 connected looping-roller may be changed in accordance with the changed speed of the feed-rolls, substantially as described.

6. In a printing-press, the combination of 35 the continuously-operating web-feeding rolls, means for changing the speed of said rolls, a movable looping-roller for the web, a vibrating lever for operating the looping-roller, a second vibrating lever below the first lever, a cam for actuating said second lever, and an 40 adjustable fulcrum on the latter lever engaging the first lever whereby the throw of the looping-roller may be changed in accordance with the changed speed of the feed-rolls, substantially as described.

45 7. In a web-printing press, the combination of means for continuously feeding a web, a vibrating looping-roller coacting with the feed devices in handling the web, a vibrating lever for operating the looping-roller and a cam for 50 operating said lever; with means for changing the speed of the feed devices and a fulcrum for the lever adjustable toward and from the cam whereby the extent of the vibration thereof can be changed to compensate 55 the movement of the looping-roller for the changed speed of the feed-rolls, substantially as described.

8. The combination of continuously-acting 60 rolls for moving a web of paper, and a movable looping-roller for causing an intermittent movement of part of the web, a vibrating lever for actuating the looping-roller and a cam for operating said lever; with means for changing the speed of the rolls, and a fulcrum for the lever adjustable to and from the cam whereby the extent of the vibrations imparted thereto by the cam may be varied to

compensate the movement of the looping-roller for the changed speed of the feed-rolls, substantially as described.

70

9. In a web-printing press, the combination of continuously-acting rolls for moving a web of paper, and a movable looping-roller for causing an intermittent movement of part of the web, a vibrating lever for actuating the 75 looping-roller; with a second uniformly-vibrating lever, and an adjustable fulcrum thereon for actuating the first lever therefrom whereby the vibrations of the first lever may be varied to compensate the movement 80 of the looping-roller for any change of speed of the feed-roll, and means for changing the speed of the feed-rolls, substantially as described.

10. The combination in a printing-press of 85 changeable-speed web-feeding rolls, a looping-roller adapted to give up a loop of web to the feeding-rollers during an impression, a lever for operating the looping-roller, and an adjustable fulcrum for said lever whereby 90 the extent of vibration of the lever and looper can be regulated in accordance with the speed of the feeding-rolls, substantially as described.

11. The combination in a printing-press, of 95 changeable-speed web-feed rolls a looping-roller adapted to take up the web fed in by the feed-rollers during an impression; a lever for operating the looping-roller and an adjustable fulcrum for said lever to regulate the extent of vibration thereof according to the speed of the feed-rolls, substantially as described.

12. The combination of means for continuously feeding a web of paper; a web-looping 105 roller coacting with the feed devices; means for changing the speed of said devices; a lever for actuating said looper, and a cam for operating the lever, with a fulcrum adjustable to and from the cam for varying the 110 movement of said lever so that it will move the looper in accordance with the speed of the feed devices, substantially as described.

13. The combination of the continuously and synchronously acting feed and delivery 115 rolls, a pair of looping-rollers coacting therewith to alternately stop and move the intermediate portion of the web, a vibrating lever for operating said looping-rollers and a cam for vibrating said lever; with means for 120 changing the speed of the feed and delivery rolls, and an adjustable fulcrum for the lever whereby the extent of vibration imparted thereto by the cam can be changed so that it will properly move the looping-rollers in accordance with the speed of the feed and delivery rolls.

In testimony that I claim the foregoing as my own I affix my signature in presence of two witnesses.

ARTHUR E. DOWELL.

In presence of—

JAMES R. MANSFIELD,
T. H. ALEXANDER.
